RHODE ISLAND.

TEMPLE HINGE.

Application filed December 15, 1925. Serial No. 75,570.

This invention relates to improvements in the construction of hinges more especially adapted for use in connecting temples to ophthalmic mountings; and the object of 5 this invention is to so mount a pivoting bolt in the hinge as to positively lock the bolt against relative rotation therein by threading the bolt in one of the ear members of the hinge and providing a lock nut on the 10 threaded end thereof, which construction serves in addition to locking the pivot bolt against rotation, also serves by adjustment to take up wear or lost motion between the 15 interengaging hinge ears or members to obtain just the desired friction in the joint to prevent looseness of the temple.

With these and other objects in view, the invention consists of certain novel features of construction, as will be more fully described, and particularly pointed out in the appended claims.

In the accompanying drawings:

Figure 1 is a perspective view illustrating a fragmental portion of an ophthalmic frame or mounting and showing my improved hinge as connecting the temple to the end piece of the frame.

Figure 2 is an enlarged perspective view showing the hinge-plates with a plurality of 30 interengaging ears, a pivot bolt passing through the ears with the nut threaded on the end thereof.

Figure 3 is a modification showing an enlarged perspective view partly in section 35 with one arrangement of a pivot bolt threaded into one of the ears and having a lock nut screwed onto its end.

Figure 4 shows another form of hinge in which one of the plates has a pair of outside 40 or end ears, the other plate having a single ear positioned between the end ears, and the pivot bolt being passed through both side ears and threaded in one of the outside ears with the lock nut threaded onto the end of 45 the bolt.

It is found in the practical construction and operation of temple hinges for ophthalmic mountings that the pivot pin often works loose permitting a looseness in the joint and 50 permitting a wobbling motion of the temple, which is very objectionable and in some cases injurious to the wearer as the lenses are thus permitted to move about on the face out of the required set position; and to obviate this 55 difficulty, I have provided a hinge having

interengaging hinge ear members in one of which members is threaded a portion of the pivot bolt and in which we have also employed a binding nut, which construction performs two functions; first, the binding 60 nut cooperates with the threaded portion of the bolt in the ear member to serve as a lock for the bolt to effectually prevent relative rotation of the bolt during the swinging action of the temple; also this nut when employed in such a structure as that illustrated in Figure 3; where the bolt is threaded into the intermediate ear of the hinge, also serves to force the outer ear against the next adjacent ear of the hinge to bind the same together to take up wear and lost motion between the parts and prevent looseness of the 65 temple so as not to detrimentally affect the vision of the wearer; and the following is a detailed description of the present embodiment of our invention and showing a construction of hinge by which these advantageous results may be accomplished:

With reference to the drawings, 10 designates an eye-wire of a non-metallic ophthalmic mounting in which the lens 11 is set, and 12 the end piece to which is hinged the temple 13 by our improved construction of hinge 14.

These hinges may, in some cases, be constructed with hinge plates 15 and 16, see Figure 3 the plate 15 having hinge ears 17 and 18 and one or more intermediate hinge ears 19; while the plate 16 is provided with hinge ears 20 and 20^a set between the hinge 85 ears 17, 18 and 19 of the plate 15. These sets of ears are provided with an axially aligned bore to receive a common pivot bolt 21. This bolt being preferably provided with a tapered under head portion 22 to fit 90 into a correspondingly-tapered recess 23 in the ear. This bolt is also threaded through one intermediate ear 19 of the plate 15 and is provided with a lock nut 24 preferably tapered as at 25 on its inner face to engage 95 a correspondingly-shaped recess 26 in the ear 17, by which construction it will be seen that any looseness between the ears 18, 19 and 20^a, may be taken up by a rotation of the bolt to draw ear 19 against ear 20^a and if 100 looseness occurs between the ears 19 and 20 this may be taken up by setting up the nut 24. This nut also cooperates with the thread in ear 19 to form a positive lock for the bolt 105 to prevent any relative movement of the bolt 110

in its ears 17, 18 and 19. A wrench 35 is shown above the nut 24 in Figure 2.

A similar effect to that above described is obtained by the construction illustrated in

- 5 Figure 4, in which the hinge plate 27 is provided with outer or end ears 28 and 29 between which the ear 30 on the plate 31 extends. The head of the pivot bolt 32 is preferably tapered as at 33 to engage a correspondingly-shaped recess in the ear 29, while this pivot bolt is threaded in the ear 28. The outer portion of this ear is counterbored as at 34 to receive a correspondingly tapered faced nut 25, which nut serves as a lock to 10 positively prevent rotation of the pivot bolt in its ears 28 and 29; also by this improved construction of hinge, it will be seen that the pivot bolt upon being set up will obtain exactly the desired friction between the different hinge ears of the hinge, a lock nut is then screwed onto the outer end of the bolt to positively lock this bolt against any relative movement to either loosen or tighten the same thereby providing a hinge which 15 will retain the desired frictional action between the hinge ears, and if these hinge members should become worn its desired frictional action may be again restored to its original working condition by a simple adjustment of both the bolt and nut.

By forming a taper on the under side of the head and on the nut of the bolt and fitting them into correspondingly shaped counterbores in the hinge ears of the joint, 20 two advantages are obtained:—first, these members are less conspicuous giving a much neater appearance to the joint; and second, this tapered portion materially increases the frictional resistance against the relative rotation of the bolt in the bearings, thereby materially assisting in maintaining the bolt in set position after having adjusted the friction of the joint.

The foregoing description is directed solely 25 towards the construction illustrated, but we desire it to be understood that we reserve the

privilege of resorting to all the mechanical changes to which the device is susceptible, the invention being defined and limited only by the terms of the appended claims.

We claim:

1. A temple hinge comprising a pair of hinge plates having a plurality of interengaging hinge ears, each of the outer ears of the set having a tapering socket formed in its outer face, a pivot bolt extending through said ears and threaded into one of them, said bolt having a tapered head portion seated in one of said tapering sockets, and a tapered binding nut fitting into the corresponding socket in the other of said outer ears and threaded onto the end of the bolt to lock the bolt and bind the ears.

2. A temple hinge comprising a pair of hinge plates, one having spaced opposite end ears and an intermediate ear, the other of said plates having spaced ears fitted between the first mentioned ears, a pivot bolt extending through both sets of said ears having a head engaging one end ear, and a lock nut 65 engaging the opposite end ear, said bolt being also threaded through said intermediate ear.

3. A temple hinge comprising a pair of hinge plates, one having spaced opposite end ears and an intermediate ear, the other of said plates having spaced ears fitted between the first mentioned ears, a pivot bolt extending through both sets of said ears having a tapered head seated in a correspondingly shaped socket in one end ear, and a tapered lock nut seated in a correspondingly-shaped socket in the opposite end ear, said bolt being also threaded through said intermediate ear, and said bolt and nut being independently adjustable to each to regulate the friction between different sets of said hinge ears.

In testimony whereof we affix our signatures.

JOHN FIELDING.
JOSEPH P. WHITAKER.
